UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed March 23, 1923. Serial No. 627,026.

To all whom it may concern:

Be it known that I, JESSE A. B. SMITH, a citizen of the United States, residing in Stamford, in the county of Fairfield and

5 State of Connecticut, have invented certain new and useful Improvements in Typewriting Machines, of which the following is a specification.

The invention relates to typewriting machines. More particularly, the invention relates to so-called billing machines in which provision is made for feeding a succession of bill or other form-sections in a continuous web, and in a plurality of plies, to the

10 platen, and in which carbon-sheets, carried on one or more rolls of a carbon carrier, are interleaved with the web-plies; the carbon-carrier being mounted in a runway on a table attached to the platen-carriage to have line-

20 feed movement with the web toward the platen, and to be moved rearward on the table for clearing the carbons of the leading written form-sections and bringing the carbons into interleavement with succeeding

25 form-sections, at the completion of the typewriting on the leading form-sections. A machine of this general class is shown in United States Letters Patent to Wernery and Smith, No. 1,132,055, dated March 16,

30 1915. In the machine therein shown, the carbon-sheets are individual sheets secured at their rear ends to blades on the carbon-carrier, and are of a limited and predetermined length, forward from the blades, sufficient to

35 cover the leading form-sections of the work-sheet plies, and to be gripped with the latter to the platen when the carbon-carrier is in its rearward position preliminary to commencing writing on the leading form-sections.

40 Carbon-sheets necessarily become worn in use, and new sheets or fresh carbon-areas of the same sheets must be substituted from time to time for the worn ones. The interleavement of individual carbon-sheets with the plies of a multiple work-sheet web, and the attachment of such sheets to a carbon-carrier, involve time and inconvenience. Rolls of carbon-paper have therefore been substituted on the carbon-carrier for the relatively short individual sheets previously used. Rotary movement of such a roll per-

mits the desired length of sheet to be unwound therefrom and interleaved with the web-plies. The roll may then be locked 55 against rotation, so that, as in the Wernery and Smith patent, the grip of the platen on the interleaved portion of the carbon-sheet will result in forward movement of the carbon-carrier when the platen has line-space 60 movement, and so that rearward throw of the carbon-carrier will shift the interleaved portion of the carbon-sheet rearward along the web-plies. When such interleaved portion of the carbon-sheet becomes worn, the 65 roll may be unlocked and the carbon-sheet drawn forward sufficiently for detachment therefrom of the leading, worn, part, and for replacement of such part by a fresh length unwound from the roll. Obviously, 70 in such use of a carbon-roll, the operations of attaching carbon-sheets to the carbon-carrier, and of interleaving the same with web-plies, may be done once and for all,—that is to say, unless and until the roll is 75 exhausted or is to be replaced.

The web-plies have, however, heretofore been fed through the carbon-carrier, usually from the rear thereof; and whereas, as in the Wernery and Smith patent, the web-plies 80 may be compactly handled and easily fed and interleaved at the carbon-carrier with individual carbon-sheets held by blades, on the carrier, it has not been found economical as to space required, or entirely satisfactory as to the feed thereof, to pass the web-plies between the carbon-rolls for interleavement with the carbon-sheets. To 85 avoid the necessity of feeding the web-plies between the carbon-rolls, the latter have been set on the carbon-carrier to the side of the path of the web-plies through the carrier, and the interleavement has been effected forward of the rolls. This expedient, however, has involved a widening, and, heretofore, an 90 increase, in the weight, of the carrier, and, because of such additional weight, has heretofore thrown an additional burden on the platen-carriage, oftentimes resulting in sluggish or unreliable letter-feed action of the 95 latter or in disadvantages arising from the increased inertia of the platen-carriage.

An object of the present invention is the provision of means, and an arrangement of

parts, whereby a single carbon-carrying roll or holder may be made to serve for a plurality of superposed carbon-webs; and of means for separating and guiding crosswise into 5 the path of the work-sheet web, and into proper planes for interleavement with the plies of the work-sheet web, the several carbon-webs delivered by such single roll; thus eliminating much equipment and weight 10 heretofore incident to the use of a separate roll for each carbon-web. Where the work-sheet web is a fan-fold of more than two plies, or if, for other reasons, desired, there may be a roll at each side of the carbon-carrier, each roll bearing a plurality of carbon-webs.

A feature of the invention is a simple and novel style and mounting of bars for turning, toward the platen, webs brought laterally or crosswise into position behind the platen; such that the turning bars may be readily placed and removed, and may be automatically and securely locked in place.

As to this feature thereof, the invention 25 may, as hereinafter shown, be used on the carbon-carrier for turning carbon-webs, or be used elsewhere for turning work-sheet web-plies.

A further feature of the invention is the 30 provision, in conjunction with a turning bar for a carbon-web, of a blade for splitting apart the plies of a fan-fold work-sheet web with which the carbon is interleaved; the splitter being adapted to be made unitary with the turning bar and detachable therefrom, and the two together unitary with a bar for guiding the carbon into its proper plane for interleavement with the work-web plies.

40 Other features and advantages will hereinafter appear.

In the accompanying drawings,

Figure 1 is a top plan view, showing the carbon-carrier of the present invention on a 45 carbon-carrier table connected to the carriage of a typewriting machine.

Figure 2 is a view, in cross-sectional side elevation, on the line 2-2 of Figure 1.

Figure 3 is a view, in front elevation, taken 50 on the line 3-3 of Figure 1.

Figure 4 is a detail view, showing the locking device, for one of the carbon-carrying rolls, on the forward end of the roll.

Figure 5 is a detail perspective view, showing one of the posts on the carbon-carrier 55 for supporting the turning bars, and showing one of the bearings for one of the carbon-carrying rolls.

Figure 6 is a perspective view of the combined carbon turning and guiding, and web-splitting device.

The platen 10, by means of its axle 11, is journaled in side plates 12 of a platen-frame, pivoted at 13 on the side plates 14 of the 65 platen-carriage, to swing up and down be-

tween its operative position and a carbon-releasing position. The side plates 12 of the platen-frame have rearward extensions 15, which, when the platen is in operative position, rest upon a shaft or cross-tie 16 connecting the side plates 14 of the carriage. The shaft 16, therefore, supports and determines the operative position of the swinging platen-frame. It is, furthermore, a rock-shaft which carries hooks 17 for locking the 70 shiftable platen-frame in operative position. Coil springs (not shown) tend to rock the shaft 16 in such direction as to throw the hooks 17 over pins 19 on the side plates 12 of the swinging frame, and automatically so 75 act, to lock the swinging frame, as the latter comes to rest upon the shaft 16.

An extension on the left-hand hook 17 serves as a finger-piece, whereby to rock the hooks and shaft 16 backward to unlock the 80 frame 12 when the latter is to be lifted to carbon-releasing position. The frame 12 carries a table 22 over which the leading form-sections of the web are fed; and the table 22 carries a gage-arm 23 and gage 24, 85 to which latter the leading edges of the web are drawn when the platen-frame is in carbon-releasing position, for determining the 90 lengths of web to be severed.

The platen-carriage is provided with the 95 usual rear paper-table and apron 25 for guiding the webs and carbons down around and to the front of the platen, and with the usual front and rear pressure-rolls 26 and 27, respectively. The webs are led from the 100 carbon-carrier table, over and around the shaft 16 down to the platen, as shown in Figure 2. The platen-carriage is supported for movements in letter-feed and return 105 directions on the main frame (not shown) of the machine.

The carbon-carrier table is a substantially 110 rectangular frame, the front cross-piece 34 of which is fixed to and supported by brackets 35 on a bar 36, which forms part of the platen-carriage and connects the side plates of the latter. The carbon-carrier table is supported at its rear on a rail (not shown) for movement with the platen-carriage in letter-feed and return directions.

Rails 42, extending lengthwise of the side reaches 37 of the carbon-carrier table, provide a runway on which the carbon-carrier table is movable, with the carbons, forward step by step as the platen has its line-space movements, and on which the carbon-carrier may be thrown rearward a predetermined distance to withdraw the carbons from the leading form-sections of the web after typing on each sections has been completed and the platen-frame thrown to carbon-releasing position. The carbon-carrier comprises a rectangular skeleton plate 43, see Figures 1, 2 and 5, having journaled on the under side thereof rollers 44 which are grooved to re- 120 125 130

ceive the rails 42 and guide the carrier therealong. An arm 45 secured by screws 46 to the left-hand side of the carrier-plate 43 extends forward and terminates in a finger-piece 47 by means of which the operator may throw back the carrier to shift the carbons along the web.

The work-sheets, in the form of endless superposed webs 48^a, 48^b, 48^c, 48^d and 48^e, 10 are led onto the carbon-carrier table, at the rear thereof, and thence forwardly through the carbon-carrier (where, as presently to be described, they are interleaved with the carbons), to the rear of the platen-carriage, 15 down over the paper-table and apron 25, around the platen, across the printing line, and up over the table 22, as shown in Figure 2. Thus far the structure described is not substantially different from that shown in 20 the above-mentioned United States Letters Patent to Wernery and Smith, No. 1,132,055, dated March 16, 1915, to which reference may be made for a fuller or more detailed understanding of the operations above mentioned.

In the present invention, the carbons 50, in the form of endless sheets 50^a, 50^b, 50^c and 50^d, are led from rolls 51 and 52 on the sides of the carbon-carrier. The carbons 50^a and 50^c are wound as superposed webs on the roll 51 at the left-hand side of the carbon-carrier, and the carbons 50^b and 50^d as superposed webs on the roll 52 at the right-hand side of the carbon-carrier. The axles 53 and 54 of the rolls 51 and 52 are set parallel to the sides of the carbon-carrier, so that the carbons may be led therefrom transversely to and over the carbon-carrier table. Bosses 54^a on the carbon-carrier plate 43 serve as 40 bearings in which the axles of the rolls 51 and 52 are journaled for rotary movement. The forward bosses 54^a on each side of the carbon-carrier have arms 55 integral therewith; each of these arms having pivoted thereto, at 55^a, a pawl or detent 56 for engagement with a toothed wheel or rack 57, fast to the corresponding roll 51 or 52, to lock the roll against rotation. A spring-detent 58 (see Figures 1 and 3), on each pawl 56, by engagement with the corresponding arm 55 serves to hold the pawl in its ineffective, Figure 3, position, or in its effective position, in which latter position the pawl engages the teeth on the rack 57. Pins 59 on the arms 55 serve as stops to determine the ineffective positions of the pawls 56. Finger-pieces 60 on the pawls serve as means for throwing the same into and away from the racks 57.

60 It will be understood that, at the line-feed movements of the platen, the carbon-sheets are not unwound from the rolls. Upon line-feed movement of the platen, as hereinafter explained, the carbon-carrier advances toward the platen. A sufficient length of car-

bon-sheet having been drawn from its roll, the roll is locked against rotary movement by a detent 56. It is only when the length of carbon-sheet in use has become worn that the roll is released to draw off a fresh length 70 therefrom. This withdrawal may be accomplished by the line-feed movement of the platen if it is so desired.

The carbon-sheets being led over the carbon-carrier table, and onto the carbon-carrier at right angles to the feed of the web-plies 48, to the platen, it becomes necessary to provide means on the carbon-carrier for turning the carbon-sheets at right angles, so that, as finally interleaved with the web-plies 80 48, they may move with the latter to the platen. This turning of the carbon-sheets is effected by means of a series of turning bars 61, numbered also, respectively, 61^a, 61^b, 61^c and 61^d. The bars 61^a and 61^c, which take 85 care of the carbon-sheets 50^a and 50^c, respectively, from the left-hand side of the table, extend diagonally from the rearward left-hand side of the carrier to the forward right-hand side of the carrier, and the turning 90 bars 61^b and 61^d, which take care of the carbon-sheets 50^b and 50^d, from the right-hand side of the table, extend diagonally from the rearward right-hand side of the carrier to the forward left-hand side of the carrier, as shown in Figure 1. Each turning 95 bar 61 has, unitary therewith, a bar 62, which extends forwardly and rearwardly, parallel to the sides of the carbon-carrier, and which, as shown in Figure 3, have the 100 function of directing and guiding the carbon-sheet from its roll, into its proper plane for interleavement with the web-plies 48. The combined turning bars 61 and guide-bars 62 for the several carbon-sheets are 105 supported in grooves 63 in posts 64, of which latter there is one on each corner of the carbon-carrier. Each guide-bar 62 has at its front and rear end a finger 65 adapted to be set in one of the grooves of the adjacent post 110 64. The bar 61^a for the lowermost carbon-sheet 50^a is supported in the lowermost groove 63 of the front and rear left-hand post 64. The bar 61^b for the carbon-sheet 50^b is set and spaced above the bar 61^a in the 115 groove second from the bottom of the front and right-hand posts 64. The bar 61^c for the carbon 50^c is set and spaced above the bar 61^b in the third from the bottom groove 63 of the left-hand posts 64. The bar 61^d 120 for the carbon 50^d is set and spaced above the bar 61^c in the fourth from the bottom groove 63 of the right-hand posts 64. The bars, therefore, as to the posts 64 on the right and left hand sides, 125 are alternated with each other, that is to say, on each side of the carbon-carrier, are set in every second groove. It, therefore, follows that the intermediate or unoccupied grooves on each post 64 might be 130

omitted. For the purposes of manufacture, and for interchangeability of the posts, such unused grooves have not been omitted. The spacing of the grooves 63, and consequently 5 of the turning bars 61 and guide-bars 62, is such as to permit the web-plies 48, coming from the rear of the table, to pass into interleavement with the carbon-sheets without 10 fouling or being fouled by the carbon-sheets, 15 when the latter are drawn off their rolls at right angles to the path of the web-plies. The guide-bars 62, in turning the carbons into planes parallel to the web-plies, correct any angular dip of the carbon-sheets at the 20 carbon-carrier which would cause the carbons and the web-plies 48 to foul each other.

For holding the combined turning and 25 guide members 61—62 against displacement in their own planes, the bars 62 at their forward and rearward ends are provided with yokes to embrace the posts 64. The yoke, at the forward end of each bar 62, comprises a finger 66 for abutment with the inner face of the corresponding post 64, and a finger 25 67, offset forward from the finger 66, adapted to abut the outer face of the corresponding post. In setting this forward yoke onto its post, the bar is first set at a slight angle to its final correct position, and is then given 30 a combined angular and forward movement to bring the yoke into the Figure 1 position on the post. During this movement, a finger 68, forming one branch of the yoke at the rear of the bar 62, is brought against the 35 inner face of the rear post 64, and a spring-detent having a finger 69, which forms the other branch of the rear yoke, is snapped over the outer face of the rear post. This spring-detent is shown as comprising an arm 40 70 pivoted at 71 to the rearward bar 62. A spring 72 fixed at 73 to the bar 62 bears against the forward edge of the detent arm 70 and urges the latter rearward around its pivot; the rearward or locking position being determined by a stop-pin 74 on the bar 45 62. The action of the detent is automatic; and to this end, the nose of the detent is curved as at 75 to cam the detent rearward as the bar is swung into place, so as to permit 50 the finger 69 to pass the post, for ultimate engagement with the outer face thereof.

In the interleaving of the carbons with the web-plies, the lower web 48^a is drawn 55 forward so that its leading end is forward of the carbon-carrier. With the carbon-rolls 51 and 52 unlocked, a length of the lower carbon 50^a is drawn crosswise over its turning bar 61^a and then turned around and 60 brought forward under its turning bar. The lower turning bar is then locked in place. The next higher web 48^b is then drawn over the lower carbon 50^a and carbon-turning bar 61^a to a position forward of the carbon-carrier; and the successively higher carbons 50

and webs 48 set in the same manner. After the upper web has been positioned over the upper carbon, and the carbon-rolls 51 and 52 being still unlocked, the webs and the carbons are seized and drawn forward to 70 the position for printing on the leading web-form. The carbon-rolls are then locked, and the carbon-carrier given a rearward throw sufficient to draw the leading ends of the carbons slightly rearward of the leading ends of the webs, so that, at a subsequent operation, the leading ends of the webs may be pinched together without pinching the carbons. This adjustment of the webs and carbons may be effected when the platen-frame 12 is in carbon-releasing position. Thereafter the carbon-carrier is set for the throw determined by the length of the form-sections. The operation of the typewriting machine may then be as explained in the 80 Wernery and Smith patent, hereinbefore referred to. The length of the carbon in use having, however, become worn, the carbon-rolls are unlocked, the carbons drawn forward a distance sufficient to provide fresh 90 printing surfaces, and the worn length of the carbons detached.

Where the work-sheet web-plies 48 are in the form of a fan-fold, it is often desirable, as hereinbefore mentioned, to split the plies 95 of the fan-fold apart on the lines of the folds thereof, at the carbon-carrier, by the movement of the carbon-carrier rearward as the latter is operated to shift the carbons from the leading typewritten form-sections 100 of the web-plies. All of the plies of the fan-fold may thus be split apart, or the fan-fold may temporarily be left intact except for the upper ply thereof, which carries the form-sections for outside distribution. 105

In the present invention, the turning bars, or, if desired, only the upper turning bar, 110 61, may be employed to effect such splitting of the web-plies. For this purpose, the turning bar 61 (see Figures 1 and 6), in addition to having a guide-bar 62 unitary therewith, has also a forward cross-reach 76 which forms a rigid triangle with the bars 61 and 62. Projecting forward from the cross-reach 76 is an arm 77, which is offset laterally at 78. Onto the offset 78 is adapted 115 to be slid a piece 79. Downward and inward-turned ears 80 on the piece 79 form a slideway for the latter on the offset 78, and, beside serving to hold the slide to the offset 78, determine the home position of the slide by abutment of one of the end ears 80 with the forwardly-extending arm 77. The slide 79 on its distal end carries a blade or slitter 81 which projects laterally beyond the side edge of the fan-folded work-piece, so that, as the blade 81 is carried rearward with the turning bar 61 and carbon-carrier, it slits the fan-fold for a distance determined by the rearward throw of the carbon-carrier. 120 125 130

An offset 82 on the blade-carrier 79 brings the blade into the plane of the turning bar 61.

For turning the platen in line-space and reverse directions, stub-shafts 83 are journaled in the side plates 14 of the platen-carriage. These shafts have the usual hand-wheels 84; and, at their inner ends, have gears 85 fast thereto. The platen-axle 11 has also fast, to each end thereof, a gear 86. The gears 85 and 86, at each end of the platen, both mesh with a gear 88 on the axis 13 around which the platen is swung, from operative to carbon-releasing position. By means of the hand-wheels 84 the platen may, therefore, be rotated in either position to which it may be swung. Also fast to the left-hand stub-shaft is a line-space ratchet-wheel (not shown); and, for turning the ratchet-wheel to effect line-space-feed of the platen through the gears 85, 86 and 88, any well-known form of line-space mechanism may be provided.

Variations may be resorted to within the scope of the invention, and portions of the improvements may be used without others.

Having thus described my invention, I claim:

1. The combination with a typewriting machine, of a table, means for guiding a multiple-ply work-sheet web over the table to the platen of the machine, a carbon-carrier movable on the table toward and from the platen in the line of movement of the work-sheet web, a rotary spool on the carbon-carrier for holding superposed carbon-webs, means for locking the spool against rotation, and for releasing the same for withdrawal of the carbon-webs from the spool, means for guiding the carbon-webs crosswise of the path of movement of the carbon-carrier as such webs are withdrawn from the spool, and for separating the superposed web-portions thus withdrawn, for interleaving thereof with the plies of the work-sheet web, and means on the carbon-carrier for turning and directing the carbon-webs along the path of the work-sheet web.

2. The combination with a typewriting machine, of means for guiding a fan-fold work-sheet web to the platen of the machine, a table, a carbon-carrier movable on the table toward and from the platen, means for directing a carbon-web in the carbon-carrier crosswise of the path of movement of the latter, a device on the carbon-carrier for turning the carbon-web toward the platen, and means on the carbon-carrier extending from the forward edge thereof toward the platen for splitting apart the folds of the fan-fold work-sheet web.

3. The combination with a typewriting machine, of means for guiding a fan-fold work-sheet web to the platen of the machine,

a table, a carbon-carrier movable on the table toward and from the platen, means for directing a carbon-web in the carbon-carrier crosswise of the path of movement of the latter, a device on the carbon-carrier for turning the carbon-web toward the platen, and means on the turning device extending from the forward edge thereof toward the platen for splitting apart the folds of the fan-fold work-sheet web.

4. The combination with a typewriting machine, of means for guiding a fan-fold work-sheet web to the platen of the machine, a table, a carbon-carrier movable on the table toward and from the platen, means for directing a carbon-web in the carbon-carrier crosswise of the path of movement of the latter, a device on the carbon-carrier for turning the carbon-web toward the platen, and means fixed on the turning device extending from the forward edge thereof toward the platen for splitting apart the folds of the fan-fold work-sheet web by movement of the carbon-carrier, with the turning device, away from the platen.

5. The combination with a typewriting machine, of means for guiding a fan-fold work-sheet web to the platen of the machine, a table, a carbon-carrier movable on the table toward and from the platen, means for directing a carbon-web in the carbon-carrier crosswise of the path of movement of the latter, a diagonally-set bar on the carbon-carrier for turning the carbon-web toward the platen, and a blade on the diagonal bar extending from the forward edge thereof toward the platen for splitting apart the folds of the fan-fold work-sheet web.

6. The combination with a typewriting machine, of means for guiding a work-sheet web to the platen of the machine, a table, a carbon-carrier movable on the table toward and from the platen, means for directing a carbon-web in the carbon-carrier crosswise of the path of movement of the latter, a diagonally-set bar on the carbon-carrier for turning the carbon-web toward the platen, and posts on the carbon-carrier for holding the bar; the bar having yokes whereby to embrace and be held by the posts, and one of the yokes comprising a detent movable to clear its post so that the bar may be swung into and out of place.

7. The combination with a typewriting machine, of means for guiding a work-sheet web to the platen of the machine, a table, a carbon-carrier movable on the table toward and from the platen, means for directing a carbon-web in the carbon-carrier crosswise of the path of movement of the latter, a diagonally-set bar on the carbon-carrier for turning the carbon-web toward the platen, and posts on the carbon-carrier having cross-grooves therein for holding the bar elevated from the base of the carrier; the bar

having yokes whereby to embrace and be held by the posts, and one of the yokes comprising a detent movable to clear its post so that the bar may be swung into and out of 5 place.

8. The combination with a typewriting machine, of means for guiding a work-sheet web to the platen of the machine, a table, a carbon-carrier movable on the table toward and from the platen, means for directing a carbon-web in the carbon-carrier crosswise of the path of movement of the latter, a diagonally-set bar on the carbon-carrier for turning the carbon-web toward the platen, 10 and posts on the carbon-carrier for holding the bar; the bar having yokes whereby to embrace and be held by the posts, and one of the yokes comprising a detent movable to clear its post so that the bar may be swung 15 into and out of place, and a spring acting on the detent to cause the latter automatically to lock the bar in place.

9. The combination with a typewriting machine, of means for guiding a work-sheet web to the platen of the machine, a table, a carbon-carrier movable on the table toward and from the platen, means for directing a carbon-web in the carbon-carrier crosswise of the path of movement of the latter, a diagonally-set bar on the carbon-carrier for turning the carbon-web toward the platen, and posts on the carbon-carrier for holding the bar; the bar having a yoke 20 at one end to engage one of the posts and having an abutment and co-operating opposed movable detent at its other end detachably and automatically to embrace another of said posts.

10. The combination with a typewriting machine, of means for guiding a work-sheet web to the platen of the machine, a table, a carbon-carrier movable on the table toward and from the platen, means for directing a carbon-web in the carbon-carrier crosswise of the path of movement of the latter, a diagonally-set bar on the carbon-carrier for turning the carbon-web toward the platen, and posts on the carbon-carrier for holding the bar; the bar being forked 40 at its front to engage one of the posts and to permit the same to be swung around such post to bring its rear against another of said posts, and having at its rear a movable detent for locking it to the rear post, against 45 displacement.

11. The combination with a typewriting machine, of means for guiding a web crosswise behind the platen of the machine, a diagonally-set bar for turning the web forward toward the platen, and posts for holding the bar; the bar being forked at one end to engage one of the posts and having an abutment and co-operating opposed movable detent at its other end detachably to embrace another of said posts.

12. The combination with a typewriting machine, of means for guiding a web crosswise behind the platen of the machine, a diagonally-set bar for turning the web forward toward the platen, and posts for holding the bar; the bar having a yoke at its front end to engage one of the posts and to permit the same to be swung around such post to bring its rear end against another of said posts, and having at its rear end a movable detent for automatically and detachably locking it to the rear post. 70

13. The combination with a typewriting machine, of a table, means for guiding a multiple-ply work-sheet web over the table to the platen of the machine, a carbon-carrier movable on the table toward and from the platen in the line of movement of the work-sheet web, a holder at the side of the table for superposed carbon-webs, means for locking the holder against withdrawal of the carbon-webs from the holder, and for releasing the same for withdrawal of a portion of the carbon-webs from the holder, 80 means for guiding the carbon-webs crosswise of the path of movement of the carbon-carrier as such webs are withdrawn from the holder, and for separating the superposed web-portions thus withdrawn, for interleaving thereof with the plies of the work-sheet web, and means for turning and directing the carbon-webs along the path of the work-sheet web. 85

14. The combination with a typewriting machine, of a table, means for guiding a multiple-ply work-sheet web over the table to the platen of the machine, a carbon-carrier movable on the table toward and from the platen in the line of movement of the work-sheet web, a rotary spool at the side of the table for holding superposed carbon-webs, means for locking the spool against withdrawal of the carbon-webs from the spool, and for releasing the same for withdrawal of a portion of the carbon-webs from the spool, means for guiding the carbon-webs crosswise of the path of movement of the carbon-carrier as such webs are withdrawn from the spool, and for separating the superposed web-portions thus withdrawn, for interleaving thereof with the plies of the work-sheet web, and means for turning and directing the carbon-webs along the path of the work-sheet web. 95

15. The combination with a typewriting machine, of a table, means for guiding a multiple-ply work-sheet web over the table to the platen of the machine, a carbon-carrier movable on the table toward and from the platen in the line of movement of the work-sheet web, a rotary spool at each side of the table for holding superposed carbon-webs, means for locking the spools against withdrawal of the carbon-webs from the spools, and for releasing the 100 110 115 120 125 130

same for withdrawal of a portion of the carbon-webs from the spools, means for guiding the carbon-webs crosswise of the path of movement of the carbon-carrier as such webs are withdrawn from the spools, and for separating the superposed web-portions thus withdrawn, for interleavement thereof with the plies of the work-sheet web, and means for turning and directing the carbon-webs from the opposite sides of the table into and along the path of the work-sheet web.

16. The combination with a typewriting machine, of means for guiding a web crosswise at the intake side of the platen of the machine, a diagonally-set bar for turning the web forward toward the platen, a carbon-carrier frame, and posts mounted on said carbon-carrier frame for holding said bar in operative relation; the bar being forked at one end to engage one of said posts and having an abutment and a co-operating opposed movable detent at its other end detachably to embrace another of said posts.

17. The combination with a typewriting machine, of means for guiding a web crosswise at the intake side of the platen of the machine, a diagonally-set bar for turning the web forward toward the platen, a carbon-carrier frame, and posts having a series of slots on their opposed faces mounted on said carbon-carrier frame for holding said bar in operative relation; the bar being forked at one end to engage one of said posts and having an abutment and a co-operating opposed movable detent at its other end detachably to embrace another of said posts.

18. The combination with a typewriting machine, of means for guiding a web crosswise at the intake side of the platen of the machine, a diagonally-set bar for turning the web forward toward the platen, and posts for holding the bar; the bar being forked at one end to engage one of the posts and having an abutment and a spring-controlled co-operating opposed movable detent at its other end detachably and automatically to embrace another of said posts.

19. The combination with a typewriting machine, of means for guiding a web crosswise at the intake side of the platen of the

machine, a diagonally-set bar for turning the web forward toward the platen, posts for holding the bar; the bar being forked at one end to engage one of the posts and having an abutment at its other end, and a spring-controlled detent mounted on one of said posts to automatically engage and hold the abutment-carrying end of said bar.

20. The combination with a typewriting machine, of means for guiding a web crosswise at the intake side of the platen of the machine, said means comprising a skeleton framework of substantially triangular and unitary formation, one of its sides forming a guide-bar, another of its sides forming a diagonally-positioned turning bar, and a third side forming a cross-reach or support, said triangular framework being provided with a yoke at one end of said guide-bar and an abutment and spring-controlled detent co-operating therewith at its opposite end, said cross-reach or support being provided with an angularly-extended arm carrying adjustable web-splitting means, and posts for holding said triangular skeleton framework by engagement therewith of said yoke and spring-controlled detent.

21. The combination with a typewriting machine, of means for guiding a web crosswise at the intake side of the platen of the machine, means comprising a skeleton framework of substantially triangular and unitary formation, one of its sides forming a guide-bar, another of its sides forming a diagonally-positioned turning bar, and a third side forming a cross-reach or support, said framework forming an acute angle at the ends of its diagonally-positioned turning bar and being provided with a yoke at one end of said guide-bar and an abutment and spring-controlled detent co-operating therewith at its opposite end, said cross-reach or support being provided with an angularly-extended arm adjacent one of said acute angles, carrying adjustable web-splitting means, and posts for holding said triangular skeleton framework by engagement therewith of said yoke and spring-controlled detent.
